BRASSIERE

Raymond C. Cole, Hillsdale, N.J., assignor to International Latex Corporation, Dover, Del., a corporation of Delaware

Filed May 4, 1961, Ser. No. 65,028

Term of patent 14 years

(Cl. D20—4)

The FIGURE is a perspective view of a brassiere showing my new design.

The dominant feature of my brassiere resides in the criss-cross bands in the lower central region of the brassiere defining thereabove a cut-out diamond shaped area.

I claim:

The ornamental design for a brassiere, substantially as shown and described.
